UNITED STATES PATENT OFFICE.

EDWARD F. TERRY, OF NEW YORK, N. Y., ASSIGNOR TO THE TERRY, TENCH & PROCTOR TUNNELING MACHINE COMPANY, A CORPORATION OF NEW YORK.

TUNNELING-MACHINE.

No. 917,974.

Specification of Letters Patent. Patented April 13, 1909.

Application filed October 23, 1905. Serial No. 283,880.

To all whom it may concern:

Be it known that I, EDWARD F. TERRY, a citizen of the United States, and a resident of New York city, borough of Manhattan, 5 in the county and State of New York, have invented a new and Improved Tunneling-Machine, of which the following is a specification.

The primary object of this machine is to 10 cut a tunnel through the rock without the necessity of blasting and the invention consists in the parts and features and combinations hereinafter described and more particularly set forth in the claims.

15 In the accompanying drawings, Figure 1 is a plan view partially in section of a machine embodying my invention. Fig. 2 is an elevation partly in section. Fig. 3 is a front view partly in section. Fig. 4 is a 20 vertical cross section, taken on the line $z-z$ of Fig. 2. Figs. 5 to 11, inclusive, are details. Fig. 12 is a modification.

There are nine gangs of drills which I will refer to as the central gang A, side 25 gangs B', B², B³, B⁴ and the corner gangs C', C², C³, C⁴. The central and side gangs are of such size and location that in their 30 movements hereinafter described they cover substantially the whole field of the end of the tunnel, the pathway of the side gangs adjoining the pathway of the central gang.

The gangs of drills above referred to are supported and operated so that they receive the following movements: (1) the recipro- 35 cating drill movements; (2) a bodily forward feed movement; (3) a sidewise move- 40 ment transverse to the tunnel line and preferably in a circle, with the axis of the tunnel as a center; (4) when required, a sidewise canting movement toward either side of the tunnel; (5) when required, a vertical cant- 45 ing movement toward the top or the bottom of the tunnel; (6) when required for chang- ing of drill-heads or other purposes, a bodily backward movement.

I will now describe the form in which I prefer to build the structure for supporting the drill-gangs and imparting to them the motions above referred to.

50 D is a carriage supported by the two pairs of wheels E', E², F', F². This carriage carries its own engine shown (Fig. 1) as a four-cylinder engine with the cylinders

mounted in pairs G' and G²; power for the engine is supplied from any suitable source 55 through pipe X and branches x' and x² (Fig. 4). The pair of cylinders G', G², are adapted respectively for driving its wheels E' and E², to impart to the carriage the forward feeding movement or the reverse, and 60 for simultaneously imparting the sidewise rotating movement to the drill-gangs. The carriage D also carries the means or a portion of the means (as, for example, the air storage tank H and its appurtenances) utilized 65 for supplying the air for the pneumatic operation of the drills.

I is the main tool-head fixed to the forward end of the rotating hollow shaft J having its bearings in the frame D. This 70 main tool-head I carries the pneumatic cylinder K from which the central gang-drills A are operated; also, the cylinders L', L², L³ and L⁴ from which the side-drill-gangs are respectively operated; also, the cylinders 75 M', M², M³ and M⁴ by which the corner drill-gangs are respectively operated.

Having now described the general features of the machine as I prefer it, I will proceed to describe the same more in detail.

The carriage D is composed of a horizontal frame consisting of the transverse girders d', d², d³ between which is built a platform d⁴ constituting the floor of the engine room for the engines G', G². Resting upon said girders d', d² and d³ is the arch d⁵ conforming approximately to the roof of the tunnel and forming the ceiling for the engine room of the engines G', G². This arch will taper very slightly from front to rear so as to provide for the canting of the carriage.

d⁶, d⁷ are diverging lugs by which the girder d' is supported upon the wheels E' E².

d⁸, d⁹ are a corresponding pair of lugs by which the girders d², d³ are supported upon the wheels F', F². Box girders d¹⁰, d¹¹ and girders d¹², d¹³ connect the lugs fore and aft and carry journals for the shafts e', e²; f', f² upon which the wheels are fixed. The rear 100 bearing j' is mounted upon the top of the rear girder d' and the forward bearing j² is mounted upon the top of the forward girders d², d³.

The storage tank H is mounted in suitable 105 framework consisting, for example, of the

uprights H' , H^2 and the horizontals H^3 . An opening N is left between the lugs on opposite sides and beneath the girders d' , d^2 , d^3 through which the workmen can pass the carriage.

The engine cylinders G' may be connected so as to drive the wheels F' , F^2 (either or both) as follows: g' is a chain through which a sprocket on the engine shaft drives a sprocket g^2 fixed to the sleeve g^3 mounted on the rotatable shaft g^4 . One end of the sleeve g^3 carries the clutch member co-operating with a clutch g^5 splined to the shaft g^4 , and the other end of the sleeve g^3 carries a beveled gear g^6 which meshes with a beveled gear g^7 fixed to the shaft g^8 extending across the carriage and carrying at its opposite end a beveled gear g^9 meshing with a beveled gear g^{10} fast to the end of a sleeve g^{11} mounted on the rotatable shaft g^{12} and carrying at its opposite end a clutch member adapted to engage the clutch g^{13} splined to the shaft g^{12} . It will now be seen that by shifting the clutches g^6 and g^{13} , the engine cylinders G' may be made to drive either or both the shafts g^4 and g^{12} , and that by reversing the engine cylinders G' , either or both of said shafts may be driven in either direction, and for communicating corresponding movements and control to the wheels F' , F^2 it only remains to connect the shaft g^4 with the wheel shaft f' by the worm g^{14} and gear g^{15} and to connect the shaft g^{12} with the wheel shaft f^2 by the worm g^{16} and gear g^{17} .

When the wheels F' , F^2 are both driven abreast, the axis of the shaft J will be maintained in alignment with the axis of the tunnel and the bore will be continued straight ahead. When, however, either one of the wheels is driven slightly ahead of the other, the shaft J' will be canted toward the side of the backward wheel and the bore will be continued in a curve toward that side.

In order to cant the shaft J up or down so as to continue the bore either in a downward or upward curvature, the wheels E' , E^2 are provided with the means of adjustment shown in detail in Fig. 5. The wheel has its bearings in a frame e^4 which slides in a guideway e^5 and is provided with a set screw e^6 for adjusting its position in said guideway. By supporting the rear end of the frame temporarily on a jack at the inclination of the shaft J desired, the set screws e^6 of the wheels E' , E^2 respectively, can be set so as to adjust the wheels for the desired degree of inclination.

It will now be obvious that by the adjustment of the set screws e^6 and by controlling the speed with which the wheels F' , F^2 are driven, a resultant cant of the carriage D may be obtained to incline the shaft J at any desired angle to the axis of the tunnel and thus continue the bore at a curvature in

any desired direction, either upward, downward, to either side or in any intermediate direction.

The engine cylinder G^2 may be connected to rotate the main drill-head I as follows: The chain g^{18} connects the sprocket on the engine shaft with a sprocket g^{19} fast to the rotatable shaft g^{20} on the opposite end of which is fixed the pinion g^{21} driving the inside gear g^{22} fixed to the main drill-head I .

The main drill-head I may be constructed as follows: i is the hub containing the central cylinder K . To the front and rear of this hub are bolted the plates i' and i^2 and from between these plates radiate the four arms i^3 , i^4 , i^5 , i^6 . Each arm is built of angle irons and plates and the hub and arms together constitute a spider upon which the circular rim i^7 of the head I is fixed. The internal gear g^{22} , already referred to, is fixed to the front of this rim and cylinders L^1 , L^2 , L^3 , L^4 are fixed inside this rim at the extremity of each arm. Projecting horizontally from the rim i^7 are the four arms i^8 , i^9 , i^{10} , i^{11} , the extremities of which are, respectively, braced from the plate i^7 by the boxes i^{12} , i^{13} , i^{14} and i^{15} so that each arm and its brace, in conjunction, form substantially a bracket carrying the cylinder for a corner drill-gang. Boxes i^{12} , i^{13} , i^{14} , and i^{15} are preferably formed with flat sides, a perpendicular front, and an inclined top slanting from a point adjacent the front of each box to the point at which it is secured to the front plate i^7 of the drill head I , as shown in the case of box i^{13} in Fig. 2; these boxes in addition to serving as braces for arms i^8 , i^9 , i^{10} , and i^{11} , afford protection for the corner drill gang cylinders M' , M^2 , M^3 and M^4 mounted adjacent the lower front edge of the boxes respectively.

i^{16} are openings fore and aft through the main head I for the passage of workmen.

The compressed air for operating the drills is supplied from a source outside the tunnel, enters this apparatus through the pipe h^4 , the storage tank H , the pipe h^5 and through the stuffing box h^6 , into the rotating shaft J through which it passes, from which it proceeds through the openings j^3 into the passage j^4 in the steel casting j^5 and thence into the passage j^6 of the hub i whence it is distributed to the various cylinders and controlled by suitable valves to automatically operate the drill pistons therein in a manner familiar to those skilled in the art of pneumatic drills.

a is the head by which the central gang of drills A is carried. This head or carrier is composed substantially of two pairs of girders a' , a^2 , a^3 , a^4 , forming substantially a cross with each other. As shown (Fig. 3) the girders a^3 , a^4 are continuous from end to end, while the girders a' , a^2 are each in two sections extending from opposite sides of

a^3 , a^4 adjacent the center thereof. As desired, girders a' , a^2 may in turn be made continuous, or both sets of girders may be made continuous and adapted to cross adjacent the center. These girders are held in position by being secured at the rear by web plates to a steel casting a^6 containing the rearwardly extending guides a^7 and forwardly extending guides a^8 within the head itself. The head or carrier a is supported upon the four guide-rods a^9 that extend from the back to the front of the head I and thence forward through the guides a^7 , a^8 of the head a .

15 The piston-rod l of the cylinder K is connected with the center of the casting a^6 . Thus, the operation of the cylinder K is to reciprocate the drill-head or carrier a so as to impart to the drill-gang A the drilling movement upon the guide-rods a^9 . The individual drills comprised by the drill-gang A are held within the girders, as shown in Figs. 8 and 11. A series of plates a^{10} are constructed as slides to slide into the girders, as shown. Before sliding the plate into position, the drills are inserted in holes through the same from the rear. When the girder is filled with these drill-holding-plates, they are held in position by the key-bolts a^{11} . The heads or carriers for the side gangs B' , B^2 , B^3 and B^4 are all of the same construction and a description of one will answer for all. They correspond substantially with the central head or carrier excepting that in the side heads the girders by which the drills are held are arranged parallel instead of crosswise of each other.

Referring to Fig. 1, b' is the girder into which is slid the series of drill-holding-plates b^{10} and which is held by the web b^{11} from the face of the casting b^6 containing the guides b^7 and b^8 on the guide-rod b^9 . Rods b^{12} connect the webs b^{11} transversely. The piston-rod l from the cylinder is connected with the center of the casting b^6 .

The heads, or carriers, for the corner gangs of drills are all of the same construction and, therefore, a description of one will answer for all.

50 Having reference to Figs. 9 and 10, the piston-rod c carries at its front end a steel casting c' containing a screwthreaded projection c^2 upon which is screwed the drill-holding-plate c^3 held by the key c^4 . The drills are introduced into the holes through the plate c^3 detached. It is then screwed onto the casting c' and keyed by c^4 .

The corner drill-cylinders have an independent swinging movement whereby the direction of the corner drills may be adjusted with reference to the radial plane from the axis of the tunnel which may be described as follows. In this regard, all of the cylinders M' , M^2 , M^3 , M^4 correspond 65 with each other, and a description of one

will do for all. The cylinder is provided with side trunnions m which have their bearings in the side members of the supporting-arm as i^8 , enabling the cylinder to be swung in the direction indicated by the arrows in Fig. 2, from a position in radial plane to the position inclined thereto, as shown in Fig. 2, or even farther, if desired.

In order to lock the cylinder at any desired inclination, the mechanism shown in Fig. 7 is employed. Surrounding one of the trunnions is a serrated surface m' engaging with a corresponding serrated piece m^2 in which the trunnion may rotate but which is fixed to the arm member i^8 . By loosening the nut m^3 , the parts m' , m^2 may be moved to any adjustment required, and then by tightening the nut m^3 the serrations will hold the parts at said adjustment.

o' , o^2 , (Fig. 4) are water pipes extending to the front of the machine, for supplying water with which to spray the face of the rock and, if necessary, to wash the cuttings back toward the rear of the machine on the bottom of the tunnel.

To remove the rock cuttings from the front to the rear of the machine, I provide the conveying apparatus P . This consists of a series of scraping blades p pivotally secured at the upper end to a bar p' which is suspended by four hangers p^2 pivoted to the bottom of the platform d^4 . These arms are swung by the eccentric rods p^3 and eccentrics p^4 from the shaft g^8 . When the bar p' swings backward, the blades p are in vertical position so as to scrape the material backward along the bottom of the tunnel and up onto the incline p^5 from which they are discharged upon the delivery belt p^6 . When the bar p' swings forward, the following mechanism causes the blades p to oscillate upward, as shown in dotted lines in Fig. 2.

p^7 is a rocker forming a pin and slot connection with this rod and pivoted at p^9 to the bar p^7 .

p^{10} is a dog pivoted to the rocker p^8 at p^{11} and held normally in line with the rocker by the spring p^{12} with its rear end resting against the pivot p^8 of the rocker.

p^{13} is a projection fixed to the carriage-frame. As the dog passes this projection in going forward, it moves the rocker into the dotted position so as to oscillate the blades p upward. As, however, the dog passes the projection p^{13} in going backward, it moves upon its own pivot p^{11} and allows the rocker p^8 to remain in full line position so that the blades p remain vertical and act as scrapers.

The modification shown in Fig. 12, resembles in general, the construction already described, with the exception that the forward feed is produced by hydraulic ram and the compressed air is supplied from a motor

and pump mounted upon the carriage and the exhaust from the drill cylinders returns to the compressed air pumps. Within the hollow shaft J is introduced a hollow piston-rod Q and piston q. Water under pressure passes from the pipe q' through this piston-rod and piston into the space q³. A stop is provided for the rear of the piston-rod Q by the inclined arms q⁴, q⁵ pressed against 10 the top and bottom of the tunnel. The hydraulic pressure in the space q³ tends to feed the whole machine forward as fast as the action of the drills permits.

R is an electric motor mounted upon the 15 carriage D and driving an air pump S from which compressed air is forced through the passage j⁴ to supply the various drill cylinders. There will be a pump S for every two drill cylinders. The air compressed by the 20 piston s' of the pump will be sufficient to supply two of the drill cylinders and as it compresses the air behind the pistons of the drill cylinders, the action of the pump-piston s² will be to exhaust the air from in 25 front of the two drill-pistons. Since the pumps S are mounted upon the nonrotating carriage D while the passages j⁴ into which the pumps discharge are in the rotating part j⁵, it is necessary to provide the connection 30 T in which the plates t', t² are nonrotatable and the ring t³ rotates with the shaft. The ring t³ is provided with two annular grooves t⁴, t⁵ that are constantly in connection with the pump passages t⁶, t⁷. Both the grooves 35 t⁴ and t⁵ are in communication with the passage j⁴.

Having thus described my invention, I claim as new and desire to secure by Letters Patent:

40 1. In combination a carriage, a rotating cutter head carried thereby, a plurality of carriers on said head, gangs of detachable rock cutting points carried by the carriers, means whereby said carriers are mounted 45 upon said head with freedom of reciprocation to and from the same, means whereby said reciprocation is produced, and means for simultaneously advancing the carriage.

2. In a tunneling machine, the combination 50 of a rotating head, a plurality of carriers mounted on said head with freedom of reciprocation to and from the same, a gang of detachable rock cutting points for each of said carriers, and means for canting the 55 head laterally.

3. In a tunneling machine, the combination 60 of a plurality of gangs of detachable rock cutting points, a carrier for each of said gangs, a head, means whereby said carriers are mounted upon the head with freedom of reciprocation to and from the same, a carriage upon which said head is mounted, means for rotating said head, and means for simultaneously propelling the carriage.

65 4. In a tunneling machine the combina-

tion of a traveling carriage, a rotating head mounted thereon, a plurality of gangs of detachable rock cutting points, a carrier for each of said gangs, means whereby said carriers are mounted upon the head with freedom of reciprocation to and from the same, means whereby said reciprocation is produced and means whereby said points are simultaneously fed forward.

5. In a tunneling machine the combination 75 of a plurality of gangs of detachable rock cutting points, a carrier for each of said gangs, a head, means whereby said carriers are mounted upon said head with freedom of reciprocation to and from the same, 80 means whereby said reciprocation is produced, means whereby said head may be canted to change the direction of the points, a carriage supporting the head, and mechanism for propelling the carriage and means 85 for simultaneously imparting a rotary movement to the head.

6. In combination, a carriage, a head, carriers mounted upon said head, means for imparting a reciprocatory movement to the 90 carriers, a detachable gang of cutting devices for each of said carriers, an engine for propelling the carriage, means for simultaneously imparting movement to the head, and means whereby said head may be canted 95 to change the direction of action of the cutting devices during the operation thereof.

7. In combination, a plurality of detachable gangs of cutting points, a carrier for 100 each of said gangs, a head upon which the carriers are mounted with freedom of reciprocation to and from the same, a carriage, means for propelling the carriage, and means for simultaneously imparting movement to the head.

8. In combination, a carriage provided 105 with a plurality of wheels, a rotating head, a plurality of detachable cutting devices, a carrier for said devices mounted upon the head with freedom of reciprocation to and from the same, an engine, driving connections between the engine and the wheels for propelling the carriage, means for disconnecting the engine from the driving mechanism of one of the wheels and means for imparting a rotary movement to the head.

9. In combination, a carriage, a head, a plurality of cutting devices, a carrier supported on the head with freedom of reciprocation to and from the same and adapted to 115 detachably receive the cutting devices, an engine, power transmission devices between the engine and the traction members of the carriage for imparting power to propel said carriage, clutch mechanisms for disengaging the engine from the power transmission devices of the carriage, and means for imparting a rotary movement to the head.

10. In combination, a carriage, a head carried thereby, a plurality of gangs of remov-

- able rock cutting points, holders for said points having freedom of reciprocation to and from the carriage, means whereby said reciprocation is produced, means for simultaneously propelling the carriage, a plurality of detachably mounted corner drills, and means for adjusting said drills with relation to a radial plane from the axis of a tunnel being cut.
- 10 11. A tunneling machine, comprising a carriage, a head carried thereby and provided with a central gang of detachable cutter members, side gangs of detachable cutters and corner gangs of cutters, means for imparting reciprocating movement to all of the cutters, and means for simultaneously propelling the carriage.
12. In a tunneling machine, the combination of a carriage, a head rotating on said carriage, an engine, means for simultaneously propelling the carriage with the rotation of the head, gangs of drills detachably secured to the head, means for imparting a reciprocating movement to said drills, means whereby said engine may be adapted to operate to cant the head to change the direction of action of the drills and a conveying mechanism for removing the material cut by the drills.
- 30 13. In a tunneling machine, a carriage, a revolving head carried thereby, a detachable gang of cutting devices arranged centrally of the head, a bracket carried by the head, and a detachable corner drill gang supported on said bracket.
14. A tunneling machine, comprising a head carrying reciprocating drill members, means for rotating the head and means for simultaneously propelling the machine, said propelling means being adapted to be operated to change the direction of advance of said machine during the propulsion thereof.
15. In a tunneling machine the combination of a carriage, a head carried thereby, drill carriers mounted on said head, means for operating said carriers, an engine, a pair of wheels oppositely positioned one at each side of the carriage, connections between the engine and the wheels for propelling the carriage and means for disconnecting the engine from one of the wheels whereby the direction of advance of the carriage may be changed.
- In testimony whereof I have signed my name to this specification in the presence of two subscribing witnesses.
- EDWARD F. TERRY.
